United States Patent Office.

CYRUS H. LATHAM, OF LOWELL, MASSACHUSETTS.

Design No. 4,166, dated June 21, 1870.

DESIGN FOR A TABLE-CASTER.

The Schedule referred to in these Letters Patent and making part of the same.

I, CYRUS H. LATHAM, of Lowell, in the county of Middlesex and State of Massachusetts, have invented and produced a new and original Design for Table-Casters, of which the following is a specification.

The nature of my design is fully represented in the accompanying photographic illustration, to which reference is made.

General Description.

Each cup of the caster that holds the bottles is composed of a series of wires, doubled to form the bows *b*, and twisted to form the strands *e*.

Two of these strands are made longer than the rest, and are passed through the ring *D* forming the bottom of the cup, and twisted together to form the leg *C*.

The strands *e* forming the ribs of the cup are bent to the required form, and their ends bent around the center ring *D*.

The handle is composed of strands of wire twisted together, and bent at the center to form the loop *F*.

The wires are then twisted together from about the

point *B*, to form the thick part of the handle, which is extended down to the tops of the cups, and the ends are then twisted into the braces *f g*.

The cups and handle are united by means of the braces, the upper ones, *f*, being twisted around the rib of a cup at *c*, and the lower ones are connected with the bottoms of the cups.

The accompanying photograph represents a caster made of twisted wire; but I do not wish to be understood as limiting my design to any special mode of construction, as I claim the right to vary it so long as the general configuration is retained by me.

Claim.

I claim as my invention—

The design for a table-caster, substantially as described, and illustrated in the accompanying photographs.

CYRUS H. LATHAM.
